UNITED STATES PATENT OFFICE

2,184,047

COMBINED MOTOR VEHICLE SERVICE
CABINET AND TABLE

John R. King, Dallas, Tex.

Application November 2, 1938, Serial No. 238,455

-3 Claims. (Cl. 155—123)

My invention relates to a combined motor vehicle service cabinet and table and has as one of the principal objects thereof the provision of such a device so constructed and arranged as to be quickly attached to the back of the front seat of said motor vehicle to provide a readily adjustable table and serving cabinet for the tonneau of said vehicle.

Another object of my invention is to provide a device of the character described capable of installation in motor vehicles already in use without modifying the same.

A further object of my invention is to provide a device of the character described which is simple in construction, durable in use, efficient in operation and economical in manufacture.

An important object of my invention is to provide a device of the character described capable of being quickly attached to and detached from the back of the front seat as desired.

Other objects and advantages will be apparent from the following description, appended claims and annexed drawing.

Referring to the drawing wherein like reference characters designate like parts throughout the several views:

Figure 1 is a perspective view of my invention as applied to the back of a front seat of a motor vehicle and illustrating the table top or service board in extended position.

Figure 2 is a vertical sectional view of my invention in attached position on the back of the front seat.

Figure 3 is a sectional view taken on the line 3—3 of Figure 2.

Figure 4 is a detail perspective view in section illustrating the upper end of one of the channel members connected to the rear face of the cabinet.

In practicing my invention, I provide a motor vehicle seat 5 formed with the usual back 6 having a rear wall 7 to which is attached, by means of screws 8, upper and lower pairs of U-shaped brackets 9. Detachably seated in and supported by said brackets 9 are downwardly disposed ends 9a of hook-shaped supporting members 10, the opposite ends of said members extending outwardly from the wall 7 and having fixed thereto upper and lower ends of channel members 11.

The channel members are arranged in parallel relation, one adjacent each end of the back 6 and their channels disposed towards each other. One side wall of each channel member has secured thereto, by means of screws 12, the rear wall 13 of a service cabinet 14, the latter being

fashioned with a front wall 15 equipped with hinged doors 16 for permitting access therein. The lower end of the front wall 15 tapers downwardly towards the rear wall thereof to provide foot space for the occupants of the tonneau.

The cabinet is closed at the upper end thereof by a top wall 16a having an upper face disposed in a horizontal plane for a purpose hereinafter set forth. The channel members 11 are provided, in the end walls thereof, with lengthwise extending slots 17 in which are slidably mounted trunnions 18 fixed to and extending laterally from one end of a table top or service board 19. The table top or service board 19 is of a thickness permitting the latter to have a sliding fit between the respective side walls of the channel members. The side walls of the cabinet 14 have pivoted thereto adjustable legs which when extended contact with the lower ends of the members 11 to support the cabinet in an upright position when detached from the seat.

The serving board 19, when not in use, is positioned between the channel members 11 and concealed therein by means of the cabinet 14. When it is desired to use the table top or serving board, the latter is raised upwardly in the channel members until the trunnions engage the upper end of the slots 17 and in this position the board 19 is pivoted outwardly and downwardly onto the top wall 16a of the cabinet, the latter coacting with said board to support the same in a horizontal and usable position.

From the foregoing it will be apparent that I have provided a simple and efficient device providing a readily accessible serving board and cabinet for the occupants of a tonneau of a motor vehicle or the like and which is so constructed and arranged that the cabinet cooperates with the board to maintain said board in a horizontal position when extended for use.

It is obvious that the invention is not confined to the herein described use therefor as it may be utilized for any purpose to which it is adaptable. It is therefore to be distinctly understood that the invention is not limited to the specific construction as illustrated and described, as the same is only illustrative of the principles of operation which are capable of extended application in advance forms, and that the invention comprehends all construction within the scope of the appended claims.

What I claim is:

1. In combination with a service cabinet having rear and top walls, spaced channel members secured to said rear wall and formed with length-

wise extending slots having upper ends disposed above said top wall, supporting members carried by said channel members and formed with sections for detachable connection to members on the back of a motor vehicle seat whereby to support said cabinet on said back, a serving board interposed between said cabinet and said back and embraced by said channel members, and trunnions carried by said board and slidable upwardly within said slots for engagement with said upper ends to position said board above said top wall whereby to permit said board to be pivoted outwardly to assume a horizontal position, said top wall of said cabinet coacting with said board for maintaining the latter in said horizontal position.

2. A device of the character described, comprising, a serving board supporting device having a rear face, spaced channel members secured to said face and provided with lengthwise extending slots having upper ends disposed above said device, supporting members carried by said channel members and formed with sections for detachable connection to members on the back of a motor vehicle seat whereby to support said cabinet on said back, a serving board embraced

by said channel members and concealed against said back by said device, and trunnions carried by said board and slidable within said slots for engagement with said upper ends of the latter to position said board above said device whereby to permit said board to be pivoted outwardly over said device to assume a horizontal position, said device coacting with said board to maintain the latter in said horizontal position.

3. In combination with a service cabinet having a top wall and provided with means for detachable connection to members on the back of a front seat of a motor vehicle, spaced guide members fixed to said cabinet at the rear thereof adjacent said back, a serving board slidably carried by said guide members adjacent said rear of said cabinet and slidable in said guide members to a position above said cabinet, and means pivotally connecting said board to said guide members to permit said board to be operated from said position to a horizontal position overlying said cabinet, said top wall of said cabinet coacting with said board to maintain the latter supported in said horizontal position.

JOHN R. KING.
